REFRIGERATOR TRAY

Charles Daum, Forest Hills, N. Y.

Application February 6, 1935, Serial No. 5,177

3 Claims. (Cl. 211—77)

This invention relates to improvements in rotary trays, being particularly directed to a novel construction applied for use in refrigerators or the like.

5 Broadly, it is an object of this invention to provide for a tray capable of disposition in a refrigerator or the like, wherein there is disposed upon a base, a rotary table supported in spaced relationship with respect to said base, for rotary 10 movement, and having dished formations on its carrier surface to provide for disposition of receptacles for various food products, or the like.

Specifically, it is an object of this invention to provide for a tray of the class specified, wherein 15 a plurality of plates forming respectively a base and rotatable table, are provided with centrally upstanding pillars, one serving as a sleeve with respect to the other, whereby the table, dished to carry a plurality of receptacles, may be supported 20 for rotation in spaced relationship with respect to the base, the base and table structures, after assembly, being locked to permit only rotary movement.

These and other advantages, capabilities and 25 features of the invention will appear from the subjoined detailed description of one specific embodiment thereof illustrated in the accompanying drawing, in which

Figure 1 is a plan view of the device.

30 Figure 2 is a front elevation taken in section along lines 2—2 of Figure 1.

Figure 3 is a front elevation in section, of the pillar assembly.

Referring to the reference characters in the 35 drawing, numeral 10 represents a base formed of a metallic stamping and having an aperture 11 centrally thereof, in which aperture there is disposed upstanding pillar 12, said pillar being fixed with respect to the base by crimping to form circular bead 13 adjacent the upper surface of the base, and spinning the edges thereof to form circular flange 14 below the lower surface of the base, to form a firm mounting for the upstanding pillar 12 with respect to said base.

40 45 Numeral 15 represents a table formed of stamped metal, having a series of dished portions 16, said table having a central aperture 17, in which is disposed upstanding pillar or sleeve 18 of diameter greater than pillar 12, as to form a sleeve therefor, said pillar or sleeve 18 being crimped to form bead 19 adjacent the upper surface of said table, and spun to form flange 20 for gripping the peripheral surface adjacent aperture 17 below the lower surface of the table, to

provide for a firm mounting for upstanding sleeve 18 with respect to said table.

To space the table 15 with respect to the base 10 there is provided an annular ring or washer 21 of diameter greater than the bead 13 on pillar 12, 5 and adapted to rest on the base adjacent such bead, said ring having its lower surface 22 contacting the upper surface of base 10, and its upper surface 23 contacting the under surface of flange 20 of the sleeve 18, such ring being freely movable 10 with respect to the base, table, or their respective pillars.

As shown in Figure 2, receptacle 24, of a structure conforming to the dished surfaces 16 formed on the table, is adapted to be disposed in such dished surface as to be maintained against displacement when disposed on the table, and the latter is rotatably displaced, such receptacle being separable for disposal and removal from said table when desired. 15 20

To maintain the respective pillars and the base and table associated therewith from lateral displacement with respect to one another, stop member 25 having a shank 26 and a head 27, is disposed, so that its shank is wedged into the 25 open end of pillar 12 and its head projects beyond the open end of sleeve 18.

In assembly, the crimped pillar 12 is spun to form flange 14, for fixing the pillar to the base; crimped sleeve 18 is spun with respect to table 15 30 35 to fix sleeve 18 to the table. Annular ring 23, of a washer formation, is dropped over pillar 12 to rest on the table 10 adjacent crimped formation 13. The table assembly is then disposed on the base assembly by sliding sleeve 18 over pillar 12, with the undersurface of the table, particularly 40 the flange 20, resting on the annular ring or washer 23. The shank 26, of locking member 25, is forced into the free end of pillar 12, so that its head projects beyond the free end of sleeve 18. 45

The above assembly, wherein there are formed dished portions, which may be varied in contour and conformation over the specific circular formation herein shown, may then have disposed in such dished portions, receptacles of corresponding sections, in the particular instance, the circular dished portion having a cooperating circular receptacle. 45

It is obvious that various changes and modifications may be made to the details of construction 50 without departing from the general spirit of the invention as set forth in the appended claims.

I claim:

1. In a device of the class described, a base, an 55 upstanding hollow pillar interlocked therewith

- centrally thereof, a table, and an upstanding sleeve interlocked therewith centrally thereof, said sleeve being disposed on said pillar whereby to permit rotation of the table with respect to said base, and means disposed in said pillar and projecting beyond said sleeve, providing a stop for preventing lateral displacement of said table with respect to said base, and an annular member surrounding said pillar and resting between said base and table to provide a bearing surface therebetween, and a dished formation on said table for insertion of receptacles therein.
2. In a device of the class described, a base, an upstanding hollow pillar interlocked therewith centrally thereof, a table, and an upstanding sleeve interlocked therewith centrally thereof, said sleeve being disposed on said pillar whereby to permit rotation of the table with respect to said base, means carried at the free end of said pillar

and resting against the free end of said sleeve, for providing a stop against lateral displacement of said sleeve with respect to said pillar and a bearing member surrounding said pillar and acting against surfaces on said base and table.

3. In a device of the class described, a base, an upstanding hollow pillar interlocked therewith centrally thereof, a table, and an upstanding sleeve interlocked therewith centrally thereof, said sleeve being disposed on said pillar whereby to permit rotation of the table with respect to said base, and means disposed in said pillar and projecting beyond said sleeve, for providing a stop against lateral displacement of said sleeve with respect to said pillar, and a bearing member surrounding said pillar and acting against surfaces of said base and table.

CHARLES DAUM.
